UNITED STATES PATENT OFFICE.

LEON BLOCH, OF BROOKLYN, NEW YORK.

DESIGN FOR A BATH-TUB AND BASIN FITTING.

53,558.

Specification for Design.

Patented July 15, 1919.

Application filed March 21, 1919. Serial No. 284,209. Term of patent 7 years.

To all whom it may concern:

Be it known that I, LEON BLOCH, a citizen of the United States of America, residing at Brooklyn, in the county of Kings and State of New York, have invented a new, original, and ornamental Design for a Bath-Tub and Basin Fitting, of which the following is a specification, reference being had to the accompanying drawing, forming part thereof.

In the drawings:—

Figure 1 is a front view of the plumbing fixture, and

Fig. 2 is a side view of the same.

I claim:—

The ornamental design for a bath tub and basin fitting, as shown.

LEON BLOCH.

Copies of this patent may be obtained for five cents each, by addressing the "Commissioner of Patents, Washington, D. C."
